(57) **CLAIM**

The ornamental design of a water purifier for hot and cool water, as shown and described.

DESCRIPTION

FIG. 1 is a perspective view of a water purifier for hot and cold water showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof showing a water discharge unit extended in a downward direction; and,

FIG. 9 is a perspective view thereof showing the water discharge unit protruded in a frontward direction.
